DESIGN FOR A PILE FABRIC

William H. Rollinson, New York, N. Y.

Application October 28, 1936, Serial No. 65,551

Term of patent 3½ years

To all whom it may concern:

Be it known that I, William H. Rollinson, a citizen of the United States of America, residing in Manhattan, county of New York, and State of New York, have invented a new, original, and ornamental Design for a Pile Fabric, of which the following is a specification, reference being had to the accompanying drawing, forming part thereof, wherein,

The figure is a plan view of a piece of pile fabric showing my new design.

The design consists of an arrangement of the cut pile fabric, with its raised area, forming alternating parallel figures, and creating a dual color tone, as shown.

I claim:

The ornamental design for a pile fabric, substantially as shown, and described.

WILLIAM H. ROLLINSON.
